F. E. BARTZ.
QUICK ADJUSTABLE MONKEY WRENCH.
APPLICATION FILED OCT. 2, 1920.

1,392,391.

Patented Oct. 4, 1921.

UNITED STATES PATENT OFFICE.

FRANK E. BARTZ, OF PITTSBURGH, PENNSYLVANIA.

QUICK-ADJUSTABLE MONKEY-WRENCH.

1,392,391.

Specification of Letters Patent.

Patented Oct. 4, 1921.

Application filed October 2, 1920. Serial No. 414,310.

To all whom it may concern:

Be it known that I, FRANK E. BARTZ, a citizen of the United States, residing at Pittsburgh, in the county of Allegheny and State of Pennsylvania, have invented certain new and useful Improvements in Quick-Adjustable Monkey-Wrenches, of which the following is a specification.

This invention relates to wrenches, and particularly to monkey wrenches, and the general object of this invention is to provide very simple means whereby the jaw of the wrench may be held in its adjusted position, or may be readily unlatched so that it may be shifted to readjust it.

A further object of the invention is to provide a device of this character in which the movable jaw is quickly shiftable to any desired degree, and in which the movable jaw is held tightly against thrust, and in which the locking device may be readily shifted to its inoperative position to permit the adjustment of the movable jaw, and is resiliently urged to its locking position to hold the movable jaw.

Other objects will appear in the course of the following description.

My invention is illustrated in the accompanying drawings, wherein:—

30 Figure 1 is an elevation of a wrench constructed in accordance with my invention, the handle being partly broken away;

35 Fig. 2 is a fragmentary elevation of a portion of the wrench, showing the handle in section to show the locking device in its locking position;

Fig. 3 is a like view to Fig. 2 but showing the locking device in its inoperative position;

40 Fig. 4 is a perspective view of the locking plate.

Referring to these drawings, 10 designates the shank of the wrench having thereon the handle 11 and provided with the fixed jaw 12. These parts may be of any suitable or usual character. Mounted upon the shank 10 is the slide 13 embodying the movable jaw 14. This slide is formed to slidably embrace the shank 10 and shift longitudinally thereon. Attached to the sliding jaw and extending therefrom parallel to the shank 10 is the rod 15, which is shown as circular in cross section, and which may shift into or through a bore 16 extending longitudinally through the handle parallel to

the shank 10. Under ordinary circumstances, the handle will not be bored entirely through but will have a bore nearly the length of the shank 15 which will permit the jaw 14 to be shifted from a position 60 against the jaw 12 to its maximum distance therefrom without the rod 15 projecting from the rear end of the handle.

Mounted upon the shank 10 and abutting against the inner end of the handle and practically forming part thereof is a hollow casing 17 through which the rod 15 passes and which contains a coiled spring 18 through which the rod 15 passes. This coiled spring at one end bears against the 70 end wall 19 of the casing. Disposed within the casing or housing is a locking plate 20 whose inner end is mounted for oscillation or rocking movement. I have illustrated this inner end as being mounted within a 75 notch 21 formed in the edge face of the shank where the shank passes through the casing or housing 19, but I do not wish to be limited to this particular means for mounting the inner end of this locking plate 80 20. I have also illustrated this locking plate as being angular in form, that is extending outward from the notch 21 parallel to the adjacent face of the handle, then extending parallel to the shank, and then extending again outward to the outer face of housing 17. At its outer end this locking plate is reduced in width, as at 22, and extends out through a slot 23 in the end face of the housing. The extremity of this plate 85 is provided with a finger piece in the form of a button 24. The spring 18 bears against this locking plate and urges it toward the butt end of the handle. When the locking plate is free and is shifted by the spring into 90 the position shown in Fig. 2, the walls of the perforation 25 in the locking plate bind on the rod 15, and the greater the pressure on this rod 15 and on the jaw 14 tending to move the jaw toward the handle, the 100 greater will be the binding action of the locking plate on the rod 15. Thus it will be impossible to shift the jaw 14 toward the handle with the locking plate in the position shown in Fig. 3. When it is desired to shift 105 the locking jaw, however, the button 24 is forced toward the jaws, which turns the locking plate into a position at right angles to the axis of the rod 15, and under these circumstances the rod 15 can shift smoothly 110

and easily through the locking plate, thus permitting the movable jaw 14 to be adjusted longitudinally upon the shank. As soon as the button 24 is released, the spring 18 will urge the locking plate again into angular relation to the rod 15 and latch or lock the rod.

Inasmuch as the principle of this device might be embodied in many forms, I do not 10 wish to be limited to the exact details of construction except as defined in the appended claims. The use of the device will be obvious from what has gone before.

I claim:—

15 1. A wrench of the character described including a shank having a handle portion and a fixed jaw at its end remote from the handle portion, a movable jaw slidably mounted on the shank for movement toward or from the 20 fixed jaw between the handle and the fixed jaw, a rod attached to the movable jaw and extending parallel to the shank, the handle being provided with a longitudinally extending bore through which said rod travels at 25 all times, a locking device for the rod disposed at that end of the handle adjacent the movable jaw embodying a locking plate having an aperture approximately the diameter of the rod and through which the rod passes, 30 said plate being fulcrumed at its inner end on the shank for swinging movement parallel to the shank and rod, the outer end of the shank forming a finger piece, and a spring urging the plate out of a position 35 at right angles to the rod.

2. A wrench of the character described including a shank having a fixed jaw at its outer end and a handle at its inner end, the handle being provided with a longitudinally 40 extending bore parallel to the shank, a slide- able jaw mounted upon the shank and hav- ing a rod extending parallel to the shank and shiftable with the movable jaw, said rod extending into the bore and being movable 45 therein, a housing mounted upon the shank at the junction of the shank and handle and

through which the rod passes, said housing being open on its end facing the handle and having its open end abutted against the adjacent end of the handle, a locking plate disposed within the housing and entirely in- closed therein and having its inner end 50 mounted for rocking movement parallel to the shank, the outer end of the plate having a portion extending out through a slot in 55 the housing and provided at its extremity with a finger piece, the locking plate having an aperture approximately the diameter of the rod and through which the rod passes, and a spring disposed in the housing and 60 bearing against the locking plate and urging it toward the butt end of the handle and out of right angular relation to the rod, that end of the slot in the housing adjacent the jaws forming a stop limiting the movement 65 of the plate to a position at right angles to the rod.

3. A wrench of the character described including a shank having a handle portion and a fixed jaw at its end remote from the 70 handle portion, a movable jaw slidably mounted on the shank between the fixed jaw and the handle portion, a rod attached to the movable jaw and extending parallel to the shank, the handle being provided with 75 a longitudinally extending bore through which said rod travels at all times, a housing having an opening through which the shank passes and having a slot at its other end, that face of the housing confronting 80 the handle being open and being abutted against the adjacent end of the handle, the shank having a shoulder engaging over the outer face of the housing and holding it in place, and a locking device mounted within 85 the housing and adapted to have locking engagement with said rod, the extremity of the locking device having a finger piece ex- tending out through the slot in the housing whereby it may be manipulated.

In testimony whereof I affix my signature.

FRANK E. BARTZ.
